UNITED STATES PATENT OFFICE.

FREEBORN F. RAYMOND, 2d, OF NEWTON, MASSACHUSETTS.

NAIL MAKING, DISTRIBUTING, AND DRIVING MACHINE.

SPECIFICATION forming part of Letters Patent No. 414,952, dated November 12, 1889.

Application filed July 1, 1889. Serial No. 316,134. (No model.)

To all whom it may concern:

Be it known that I, FREEBORN F. RAYMOND, 2d, of Newton, in the county of Middlesex and State of Massachusetts, a citizen of the 5 United States, have invented a new and useful Improvement in Nail Making, Distributing, and Driving Machines, of which the following is a full, clear, and exact description, reference being had to the accompanying 10 drawings, forming a part of this specification, in explaining its nature.

The invention is an improvement upon that described in my Letters Patent No. 381,280, dated April 17, 1888; and it relates to various 15 details of construction and organization, whereby the construction of the machine is simplified and its operation improved.

It also relates to the employment, in connection with a mechanism for making or delivering 20 a gang of fastenings, of a gang of clearers for forcing or feeding the fastenings through the passages of the distributor into the fastening-carrier or holes or passages from which the fastenings are driven and for clearing said 25 passages.

In the drawings, Figure 1 is a view in vertical central section of a machine having the 30 features of my invention. Fig. 2 is a view in cross-section thereof. Fig. 3 is a view in side 35 elevation of the machine, representing the position of the parts when the clearers are elevated. Fig. 4 is a view in elevation of the same parts, representing the position of the parts when the clearers are depressed. Figs. 40 5 and 6 are detail views. Fig. 7 illustrates the connection between the nail-making devices and the nail-driving devices. Fig. 8 is a view representing the nail-feeding plate, hereinafter referred to, made of different 45 thicknesses to feed wires differing in gage or thickness.

In the drawings, A A' represent the die-rolls. Instead of being upon a horizontal line or plane, as shown in the patent above referred to, they are placed upon a vertical line or plane—that is, one over the other—so that the gang or group of wires from which the fastenings are made are fed horizontally instead of vertically. The rolls preferably 50 are of a sufficient length to enable a large number of nails or fastenings to be made, and in the drawings I have represented them as

adapted to make thirty nails simultaneously. The rolls have end bearings in suitable boxes held or supported by the frame B, and the 55 boxes of the upper roll are adjustable in relation to the boxes of the lower roll by means of adjusting-screws a'. The rolls may also have central bearings or supports a². The rolls carry or support point-forming dies a³a⁴— 60 the roll A the sections a³, and the roll A' the sections a⁴. The dies preferably are made or formed in groups of two or more from one plate or block. In other respects they preferably are like those described in said patent. 65

The cut-off devices comprise a cut-off plate C and the pressure-plate C'. The cut-off plate C extends the length of the dies carried by the rolls and may be in one piece; or if the rolls have a central bearing it may be in two pieces, 70 one upon each side of the central bearing. The bearing-plate C' is of similar shape and arrangement.

The cut-off plate C is represented as operated or moved readily by stationary or adjustable cams c and the push-rods c'. (See Fig. 5.) The pressure-plate C' is moved outward by means of the springs c². The arrangement of the dies, cut-off, and presser bar is similar to that described in the said patent and in the patent, No. 375,209, to C. C. Small, with the exception that the dies are placed closely together, and the cut-off bar and presser-bar are continuous instead of being made in separate pieces. 85

The devices for feeding the wires comprise feed-bars D D', set in recesses in the rolls A A', respectively, the roll A having the longitudinal recess d in its periphery of a width sufficient to receive the widest feed-bar which 90 it may be necessary to use, and the roll A' having the recess d' for receiving the corresponding feed-bar. The feed-bars are provided, preferably, with rough or corrugated surfaces d², and they are of the length of the 95 parts of the rolls—that is, they are long enough to include all the dies. Where a central bearing is provided the rolls, they may be made in two parts, or, in fact, they may be made of any number of parts. They are fastened to 100 the rolls, preferably, by screws, and in a manner to be easily removable therefrom, and the edge d³ of each, when attached to its respective roll, is in contact with the shoulder d⁴, formed

by the recess. The width of the surface of the feed-bars determines the extent of feed of the wires over and above that caused by the drawing and feeding action of the dies 5 $a^3 a^4$. To make a short-pointed nail, the feed-bars may be entirely dispensed with. To make short unpointed nails, the dies may be dispensed with and the feed-bars D D' substituted therefor. To vary the length of the 10 fastenings or nails, it is simply necessary to vary the width of the feed-bars by removing one set and substituting a narrower or wider set for those removed. To vary the length of each gang of fastenings, the feed-bars D D' 15 are made of different widths, and one thus formed is represented in Fig. 6. By thus varying the width of the feed-bars each gang or group of nails may vary in length to any desired extent. A portion of them may be long 20 and others short. By varying the thickness of the feed-bars wires of different thicknesses or gages may be simultaneously fed and acted upon by the single pair of rolls, so that some fastenings may be made of one length 25 and one gage, while others may be simultaneously made of a different length and of a different gage. (See Fig. 8, which shows section of feed-wire.)

In operation the wires a are fed from reels 30 (not shown) through throats or passages e in a plate or block E to the dies, there being a separate hole e for each wire and die, and the point or end of the block E preferably is brought as closely to the converging point of 35 the rolls and dies as possible. There may be placed in front of the block E the guiding-rolls $e' e^2$, between which the wires may run to the passages or holes e , and one of them preferably has an elastic covering of 40 rubber e^3 , and is set with some slight tension against the roll e^2 sufficient to prevent the wires from drawing by gravity out of position from between the rolls, but not sufficient to create any appreciable tension on the wires. 45 By arranging the feeding devices upon the die-rolls instead of separately, as in the patents referred to, these important advantages are obtained: First, the wires are relieved of undue tension, whereby each pair of dies acts 50 in a measure independently of the other, so far as drawing the wire which they act upon; second, the feeding of the wires is more uniform and is at the same time capable of far greater variation; third, the construction is 55 much cheaper and simpler. The fastenings are delivered from the rolls into the passages F, there being preferably a passage for each nail or fastening. These passages are represented as curved sufficiently to permit the 60 fastenings to fall by gravity into the vertical passages f' . These vertical passages, with the curved passages F, are preferably formed in a removable block, and the upward extensions f^2 of the passages f' provide guides for 65 the clearers G, there being a clearer for each passage f' . These clearers are of a length to extend through the passages f' and the pas-

sages h in the distributor II. The distributor H is like that shown in the patent referred to, and comprises, in substance, the lower block 70 h' , in which the lower ends of the tubes h^2 , forming the passages h , are secured, and which block has holes in continuation of said passages h , the said tubes h^2 , and the upper block h^3 , which holds the upper ends of the tubes, 75 and which has holes opening into the passages h and in line with the passages f' .

The clearers G are made, preferably, of spring-wire or piano-wire, and are attached or secured at their upper ends to a slide g , 80 which is given a vertical movement in the vertical guides g' at a suitable interval—that is, after the gang of fastenings have been made and delivered into the passages f' by means of one or more cams g^2 . In the drawings there are two cams represented, one at each end of the upper roll A, levers g^3 , links g^4 , and levers g^5 , pivoted at g^6 to brackets g^7 and connected at their upper ends by short links g^8 to the slide g . While I have represented 90 two sets of links and levers, I would not be understood as limiting myself thereto, as one set only may be used; neither would I confine myself to this method of operating the slide. The clearers G, traversing all the passages f' 95 and h into which nails or fastenings are fed, insures the proper delivery or feeding of the nails or fastenings through said passages to the carrier or other receptacle M, and they also insure the clearing of the passages, so 100 that there can be no clogging, and they are always in condition to receive the next gang or group from the nail-supplying devices.

I have represented the fastenings or nails as delivered to a carrier M, and this carrier 105 is movable, preferably, by means of the cam m , to transfer the nails to the driving devices, comprising, preferably, a templet m' and a gang of drivers m^2 . In operation the wires are led from the reels into the passages e and 110 to a position between the rolls A A', and upon the rotation of the rolls, after, of course, the ends of the wires have been severed, the wires are simultaneously fed, point-forming sections formed in the wires, and the previously-pointed sections severed and delivered to the passage f' , from which they are 115 fed through the tubes of the distributor by the clearers G. Of course, as a rule, the rolls A A' make but one revolution—that is, one 120 complete revolution of the roll points and severs a gang of fastenings, feeds the wires, and affords time for the operation of the clearers. As above stated, fastenings varying in 125 length can be simultaneously made and delivered. Of course the feed-blocks D D' may be formed integral with the rolls A A'; but it is a much better construction to make them separate or independent of the rolls, as above specified.

Having thus fully described my invention, I claim and desire to secure by Letters Patent of the United States—

1. The combination of devices for simul-

taneously feeding nails or fastenings to the passages of a distributor with a reciprocating gang of clearers G, to traverse the passages of said distributor, substantially as described.

2. The combination of a distributor having a number of passages *h* with a gang of clearers G, substantially as described.

3. The combination of a distributor having a number of passages *h*, which are curved, inclined, or otherwise bent, with a gang of clearers G, formed of flexible wire or other material to traverse said curved, inclined, or other shaped passages, substantially as and for the purposes described.

4. The combination of the block having the series of passages F *f'* with the gang of reciprocating clearers G, one for each of the passages *f'*, substantially as described.

5. The combination of the distributor H, having passages *h*, the nail receiver or carrier, and a gang of clearers G, to traverse said passages and eject the nails or fastenings into said nail receiver or carrier, substantially as described.

6. The combination, with nail-driving devices, of a nail-distributor having a series of curved or inclined passages *h* with a gang of clearers G to follow said curved or inclined passages, substantially as described.

7. The combination of the rolls A A', nail-pointing dies carried thereby, and the feed-blocks D D', carried by or formed upon said rolls, substantially as described.

8. The combination of rolls A A', a wire 35 cut-off, and the feed-blocks D D', carried by or formed upon said rolls, substantially as described.

9. The combination of the rolls A A', feed-blocks D D', formed upon or carried by said 40 rolls, pointing devices *a*³ *a*⁴, and a nail cut-off, substantially as described.

10. The combination of the rolls A A', the feed-blocks D D', formed upon or carried by said rolls, pointing devices *a*³ *a*⁴, a nail cut-off C, and presser C', substantially as described.

11. The combination of the rolls A A' and the feed-blocks D D', formed thereon or secured thereto, substantially as described. 50

12. The combination of the rolls A A', having a series of nail-pointing dies, with the feed-blocks D D', substantially as described.

FREEBORN F. RAYMOND, 2D.
